CLAIM

The ornamental design for a stand for electronic device as shown and described.

DESCRIPTION

FIG. 1 is a front perspective view of a stand for electronic device showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view showing the stand for electronic device in an alternate configuration.

The broken lines shown in the drawings depict portions of the stand for electronic device that form no part of the claimed design.

1 Claim, 9 Drawing Sheets
